UNITED STATES PATENT OFFICE

134,603

DESIGN FOR A COMBINED DENTIST'S CABINET AND X-RAY PICTURE DISPLAY SUPPORT

George E. Froelich, Two Rivers, Wis., assignor to Hamilton Manufacturing Company, Two Rivers, Wis., a corporation of Wisconsin

Application June 5, 1942, Serial No. 107,139

Term of patent 14 years

To all whom it may concern:

Be it known that I, George E. Froelich, a citizen of the United States, residing in Two Rivers, county of Manitowoc, and State of Wisconsin, have invented a new, original, and ornamental Design for a Combined Dentist's Cabinet and X-Ray Picture Display Support, of which the following is a specification, reference being had to the accompanying drawing, forming a part thereof.

Figure 1 is a perspective view of a combined dentist's cabinet and X-ray picture display sup-

port, showing my new design, with the cover in open position; and

Figure 2 is a top plan view of the same with the cover in closed position.

The dominant features of the design reside in the portions shown in full lines.

I claim:

The ornamental design for a combined dentist's cabinet and X-ray picture display support, substantially as shown and described.

GEORGE E. FROELICH.
